UNITED STATES PATENT OFFICE.

STANLEY L. BARBER, OF PASADENA, CALIFORNIA.

TREE SURGERY.

Application filed February 23, 1923. Serial No. 620,788.

My present invention is a method of tree surgery, and means for use therein; and it is a primary object of my invention to provide a simple and effective method for permanently healing the wounds of trees.

Although my invention includes or presupposes a preliminary cleaning of a wound to be healed, my invention aims not only to keep a cleaned wound dry, by excluding moisture and by permitting a drainage or a ventilation or even a forced circulation of a gas within a cavity, but it aims also at an actual strengthening of a limb or part which may have been weakened by decomposition forming a cavity therein.

For the purpose of excluding moisture from the wounds of trees while permitting an access of air thereto, my invention aims to employ means such as a downwardly sloping tube or tubes, extending into a wound that has been cleaned and provided with a closure. My tubes may not extend through the closure.

It is a further object of my invention to provide wound-closing means comprising a reinforcing element or elements secured to the sound wood by which a cleaned cavity is bounded, and extending across such cavity without filling the same; and my preferred construction involves the use of an underlying web of wire, or the equivalent, preferably covered with tarry or other yielding material adapted to exclude moisture, outside of which I may optionally apply an additional coating, preferably also reinforced, and optionally comprising hydraulic cement, which may be colored or formed in imitation of bark.

Other objects of my invention will appear from the following description and the claims appended thereto.

It is believed that the general character of my invention will be readily understood from a detailed description of a preferred embodiment and alternative embodiment thereof, taken in connection with the accompanying drawings, in which—

Fig. 1 may be regarded as a cross section of a trunk or limb of a tree having a cavity therein.

Fig. 2 may be regarded as an elevation or front view of the same cavity after the same has been cleaned and provided with a reticulated or foraminous material extending across the opening from said cavity, and

with tubular elements hereinafter referred to.

Fig. 3 is a section on the line 3—3 of Fig. 2.

Fig. 4 may be regarded as a vertical section on the line 4—4 of Fig. 2, this figure showing two alternative methods by which ventilating or drainage tubes may be held in place.

Fig. 5 is a view similar to that of Fig. 2, showing the appearance of a treated wound or cavity after tarry or other water-excluding material has been applied to the reticulated element shown in Fig. 2.

Fig. 6 is a sectional view showing the relationship of parts after all portions of my process, in one of its embodiments, have been completed.

Fig. 7 is an elevation also showing the product obtained by the process referred to, the counterfitting of bark, as indicated in Figs. 6 and 7, being optional.

Referring in detail to the form of my invention shown in the accompanying drawings, 1 may be regarded as the trunk or limb of a tree covered with a natural bark 2, and within which decay has resulted in the formation of a cavity. As a result of the removal of decomposed matter this cavity may have the form indicated at 3. In order to check decomposition within this cavity, I find it important to exclude moisture therefrom, and for this purpose I prefer to shape the lower portion of the cavity, as indicated in Fig. 4, in such manner as to permit a drainage therefrom; and I find it advantageous not to attempt to entirely fill the cavity, preferring rather to provide a suitable closure or partition across the opening thereof, and suitable means of ventilation.

To exclude atmospheric moisture from a cavity that has been suitably cleaned, and also to strengthen the limb or trunk which may have been weakened by the formation of a cavity therein, I find it advantageous to secure at the mouth of the cavity a reticulated or foraminous material, preferably metallic, and I may employ for this purpose a wire screen 4 secured by means such as the staples or tacks 5, this screen being adapted to retain in position the tubes 6, and to be otherwise entirely covered by a layer of water excluding material 7, which is preferably a plastic combination, such as a tarry product, preferably containing fibrous

material. For this purpose I may use an asphaltic or tarry composition such as is now readily obtainable for the repair of roofs, this material having a comparatively permanent plasticity, such as adapts it to the use indicated. It will be understood, in this connection, that the composition referred to must be capable of forming a tight joint at the edge of the cavity to which it is applied, and that this joint must not be readily broken when the limb or trunk of the tree is bent during a storm.

Although the tubes 6 may be secured in any suitable manner, as by contact with the mesh 4 and the tarry coating 7, I may optionally secure them by either of the methods indicated in Fig. 4. In order that the cavity 3 may remain substantially dry, I prefer to insert one of the tubes 6 at such a point as to effect a complete drainage thereof. In Fig. 4, I have indicated that this drainage tube 6^a may be secured by a staple, and I have also suggested at 6^b the possibility of providing a ventilating tube with a lateral aperture A, in order that the tube may be driven into the sound wood of a trunk or limb, and yet function properly in the ventilation of the cavity 3.

A cavity which has been suitably cleaned and provided with a water-tight closure and drainage or ventilating tubes of the character described may be regarded as fully protected against further deterioration; but I prefer to so arrange the drainage or ventilating tubes referred to that I may apply over the water excluding material 7 an additional protective coating. For this purpose I may secure, by means such as the tacks 8, an additional layer of wire screen or other reinforcing material 9, and whether or not I employ this reinforcing element, I may apply a layer of hydraulic cement, or the like, 10, this being preferably keyed in place by dovetailing extensions 11, and optionally colored or shaped in imitation of bark, as suggested at 12. It will be understood that even when I employ this outer layer of concrete, I prefer to let the outer ends of the tubes 6 extend therethrough; and I may mention that these tubes may be employed not only to facilitate a natural ventilation of the cavity 3, but also and optionally to permit the forcing of dry air or even of a disinfecting or sterilizing agent, preferably a gas, therethrough. I have not found the employment of such a sterilizing agent to be necessary, the natural circulation of air being ordinarily sufficient to prevent the formation of a mildew or other organic growth within the cavity 3. It will be obvious that the inclination of the pipe or tube 6 is intended to prevent the entrance of rain water therethrough, and that the inclination

of the lower pipe serves also to facilitate 65 drainage from the cavity 3.

While I prefer to introduce my ventilating or drainage tubes in the manner above described, the cavities in trees are sometimes of very irregular configuration, and, for this reason, I may in some cases insert tubes, in the manner suggested at 6^c and 6^d in Fig. 5, directly through the sound wood of a tree, and even at a considerable distance from any cavity. 75

It will be understood that various features of my invention might be independently employed, and that various modifications might be made without departing from the spirit and scope of my invention, 80 as the same is indicated above and in the following claims:

What I claim is:

1. The method of caring for trees in tree surgery which consists of removing the decayed part in a tree, placing a covering over the opening or entrance to the hollow cavity so formed, and providing ventilating means through the covering adjacent the top and bottom thereof. 90

2. The method of caring for trees in tree surgery which consists of placing a covering over the entrance to the hollow cavity in the tree, and inserting an outwardly and downwardly inclined ventilating tube through the covering into the hollow cavity adjacent its bottom. 95

3. The method of caring for trees in tree surgery which consists of placing a covering over the entrance to the hollow cavity in the tree and inserting downwardly and outwardly inclined ventilating tubes through the covering adjacent its top and bottom. 100

4. The method of caring for trees in tree surgery which consists of removing the decayed part of a tree to form a hollow cavity, securing a reticulated material over the entrance to the hollow cavity, applying a water-proofing plastic material to the reticulated material, securing a second section of reticulated material over the entrance in spaced relation to the first, and applying a cementitious material thereto. 105

5. The method of caring for trees in tree surgery which consists of removing the decayed part of a tree to form a hollow cavity, securing a reticulated material over the entrance to the hollow cavity, applying a water-proofing plastic material to the reticulated material, securing a second section of reticulated material over the entrance in spaced relation to the first, applying a cementitious material thereto, and inserting a plurality of ventilating through the covering so formed. 115

In testimony whereof I have signed my name to this specification.

STANLEY L. BARBER.
